CLAIM

The ornamental design for a jog dial for kitchen appliance as shown and described.

DESCRIPTION

FIG. 1 is a top perspective view of a jog dial for kitchen appliance;

FIG. 2 is a bottom perspective view thereof;

FIG. 3 is a front elevational view thereof;

FIG. 4 is a top plan view thereof;

FIG. 5 is a bottom plan view thereof; and,

FIG. 6 is a left-side elevational view thereof.

The broken lines are shown for the purpose of illustrating environmental subject matter of an exemplary kitchen appliance. The use of line shading and stippling-style shading depicts a contrast in materials. The dash-dot-dash broken lines shown in FIGS. 1-6 are for the purpose of depicting boundary line portions of the jog dial and form no part of the claimed design.
